UNITED STATES PATENT OFFICE.

MAURICE L. POWERS, OF NEW YORK, N. Y.

DESIGN FOR A FINGER-RING.

SPECIFICATION forming part of Design No. 36,083, dated September 30, 1902.

Application filed August 19, 1902. Serial No. 120,206. Term of patent 3½ years.

To all whom it may concern:

Be it known that I, MAURICE L. POWERS, a citizen of the United States, residing at New York, borough of Manhattan, county and State of New York, have invented and produced a new and original ornamental Design for Finger-Rings, of which the following is a specification, reference being had to the accompanying drawings, forming part thereof.

10 Figure 1 illustrates a plan view of a ring embodying my new design, the stone, which in the completed ring will be duly set therein, being omitted. Fig. 2 illustrates an elevation of the ring shown in Fig. 1.

15 As shown in the drawings, the leading features of my design consist in a series of upwardly-presented horn-like projections which constitute the body of the setting or stone-holding part of the ring. These several horns 20 are curvilinear in outline and gradually thicken from their points downwardly toward the body of the ring, thus representing a tapered or stem-like form, which blending together constitute the circlet or finger-embracing part of the ring, so that the exterior of

the ring at right and left of the top part of the setting has the appearance of a central rib with lateral flanges at both sides.

Referring to the drawings, *a a* are the upwardly-extending horn-like parts. *b b* are the heavier receding parts of the horns, and *c c* are the stem-like or terminal parts of the horns, which, being laid up together, constitute the circlet part of the ring, and these parts, more particularly to the right and left 35 of the head of the ring, are so laid up together that they present the appearance of a central rib *d d*, having flanges *e e* at each side thereof.

Having described my invention, I desire to 40 secure by Letters Patent—

The ornamental design for a finger-ring as herein shown and described.

In testimony whereof I have signed my name to this specification in the presence of 45 two subscribing witnesses.

MAURICE L. POWERS.
